DESIGN FOR A TEXTILE FABRIC

Moses F. Gantz, Yonkers, N. Y., assignor to The
First Textile Corporation, New York, N. Y.

Application November 4, 1935, Serial No. 59,356

Term of patent 3½ years

To all whom it may concern:

Be it known that I, Moses F. Gantz, a citizen of the United States, residing at Yonkers, in the county of Westchester and State of New York, have invented a new, original, and ornamental Design for a Textile Fabric, of which the following is a specification, reference being had to the accompanying drawing, forming part thereof.

The figure of the drawing is a plan view of a fabric showing my new design.

The design consists of a series of substantially square blocks bearing a basket weave design,

separated by areas which present a quilted appearance. The blocks are arranged in offset relation as indicated by the lower edge of the drawing. This design is repeated over the surface of the fabric in the relation indicated.

I claim:

The ornamental design for a textile fabric as herein shown and described.

In testimony whereof, I hereunto affix my signature.

MOSES F. GANTZ.
